UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

BAFFLE.

Application filed December 24, 1920. Serial No. 432,985.

My invention more particularly relates to a baffle extending across the boiler tubes of a boiler and comprising hardened plastic material, and to the method of making the 5 same.

My invention will best be understood by reference to the accompanying drawings, in which like reference characters indicate like parts, and in which Figure 1 is a vertical 10 front view of a baffle embodying my invention, with some of the parts broken away; Fig. 2 is a sectional side view of Fig. 1; Fig. 3 is a perspective view illustrating the 15 position of one of the hollow heat conducting members with reference to the boiler tubes; Figs. 4 and 5 are views similar to Figs. 1 and 2, respectively, and illustrating a slightly modified form of my invention; Fig. 6 is a perspective view similar to Fig. 20 3 and illustrating the hollow member shown in Figs. 4 and 5; Fig. 7 is a vertical sectional view taken transversely of the boiler tubes with the hollow members forming a part of the finished baffle in position and illustrating one method of introducing the 25 plastic material; Fig. 8 is a longitudinal section through the tube by which the plastic material is introduced into the baffle; Fig. 9 is a longitudinal section of the tube taken 30 at right angles to Fig. 8 and showing the wings on the lower end of the plunger in closed position; Fig. 10 is a view similar to Fig. 9, showing the wings on the lower end of the plunger in open position, and Fig. 11 35 is a transverse section taken across the tubes shown in Figs. 8, 9 and 10.

Referring, now, to the drawings, 12 are the boiler tubes of a steam boiler, here shown as arranged in staggered relation, across 40 which is installed a baffle embodying my invention, indicated, in general, in Figs. 2 and 5, by the reference character 13.

In preparing a baffle in accordance with my invention, I first install hollow members 45 14 of good heat-conductivity, and preferably formed of metal, each member comprising side walls 15 which are preferably flat and curved at their edges to conform to the boiler tubes, as indicated in Fig. 3, the 50 side walls being connected by transverse walls 16, which preferably conform to the surfaces of the boiler tubes, so that the member as a whole forms close contact and is in good thermal engagement with the boiler 55 tubes. The members 14 are of such a width that they may readily be installed by passing them diagonally between the tubes of the boiler and then turning them on edge into the position which they are to occupy in the finished baffle, the members being installed 60 in rows transversely of the tubes and above one another, to form a skeleton for the finished baffle. The members 14 are installed in position by arranging them end to end to form a horizontal row, it being understood 65 that each member may be of any desired length.

In Figs. 4, 5 and 6, I have shown a slightly modified form of my invention, in which each hollow member 14^a is provided at one 70 end with a rib 19 which engages a recess 20 formed on the adjacent end of the adjacent member 14^a, in order to secure the members in alinement.

In case a metal flame-plate is to be used, 75 the same is installed, as at 17, at one side of the hollow members, while the spaces between the members on the opposite sides thereof are closed by removable strips of the form shown at 18 in Fig. 1, which may be 80 conveniently formed of metal, each strip resting on a row of tubes and being provided with projections 18^a extending upwardly between the tubes to cover the spaces between the sides of the hollow members 14. 85

The form so prepared is now ready to be filled with plastic material, which may conveniently be introduced from the top of the baffle by inserting through a diagonal row of hollow members and between the boiler 90 tubes a tube 21, in the manner indicated in Fig. 7, the upper end of the tube 21 preferably being provided with a hopper 22 for containing a mixture of the plastic material 95 23 from which the baffle is to be formed. 95

The tube is first moved downwardly to the bottom of the form, and the material may be conveniently forced through the tube by a tool comprising a rod 24 enlarged at its lower end, as at 25, to form a bearing for 100 two wings 26, which are pivoted, as at 27, to the enlarged lower end 25. When the rod is forced downwardly, the resistance offered by the material causes the wings 26 to open to the position indicated in Fig. 10 and to force the plastic material downwardly through the tube; whereas, when the rod 24 is withdrawn, the wings collapse to the 105

position shown in Fig. 9, thus permitting the withdrawal of the tool without drawing back a substantial amount of the plastic material in the tube. While the plastic material is being forced into the baffle, the tube 21 may be moved up and down, so as to press the plastic material firmly in place, or, if necessary or desirable, a separate member may be used for packing the material. In building up the plastic portion of the baffle, the tube is moved along to the successive diagonal positions between the boiler tubes, as indicated in Fig. 1, to first form a single lower layer, the remaining layers being similarly formed. The faces 15 of the member 14 and the flame plate 17 close one side of the form for the plastic material, while the faces 15 and the strips 18 close the other side thereof. The hollow members 14 preferably form openings which are rectangular in cross-section. The tube 21 is, accordingly, preferably formed rectangular in cross-section, in order to provide for the maximum cross-sectional area of material. When the plastic material has hardened, the strips 18 are removed. The movable strips 18 may be used at each side of the baffle without employing the cast iron flame plates 17, in which case both sides of the baffle will be made up of the faces 15 of the members 14 and of the material which is initially in a plastic state.

In a baffle made in accordance with my invention, the boiler tubes serve to carry the heat away from the members 14, which, in turn, conduct the heat from the hardened plastic material, and thereby the entire baffle is maintained at a temperature lower than it otherwise have. The members 14, which are preferably formed of cast iron or other good heat-conducting material, also serve to reinforce the face of the baffle and thus prevent the face of the baffle from spalling off or eroding, due to the action of the heat. The reduction of the spalling action of the part of the baffle formed of hardened plastic material is secured by cooling the baffle in the way described and by making the faces 15 of the members 14 form a portion of the face of the baffle, thereby cutting down the surface of contact of the gases with the hardened plastic material. The members 14 reinforce the baffle, thereby making it possible to construct a strong and durable baffle which will not be damaged or affected by puffs or light explosions due to the ignition of combustible gases within the setting.

In place of forcing the plastic material through the tube 21 by means of the tool comprising the rod 24 enlarged at its lower end and provided with wings 26, the plastic material may be forced through the tube 21 by means of compressed air, or other mechanical means. In case compressed air is

used the plastic material is placed in a hopper fitted with an air-tight cover and the compressed air is introduced into the top of the hopper and forces the plastic material through the tube 21. A stationary hopper may be used and a connection made between the hopper and the tube 21 by means of a flexible hose. If so desired, the hopper may be attached directly to the top of the tube 21 and fitted with an airtight cover which would be closed after filling, and compressed air would then be introduced inside of the hopper through a flexible hose connection. With the latter arrangement the hopper 22 and the tube 21 would be moved as desired in inserting the plastic material.

What I claim and desire to secure by Letters Patent of the United States is:

1. A metallic member for a baffle, said member having relatively thin flat side walls and relatively thin curved end walls adapted to engage boiler tubes, said walls being spaced apart to form an opening in the body portion of said member. 70
2. A metallic member for a baffle having flat side walls and curved end walls adapted to engage boiler tubes, the member being provided with an opening extending therethrough and defined by said side and said end walls. 95
3. A metallic member for a baffle having flat side walls and curved end walls adapted to engage boiler tubes, the member being provided with an opening rectangular in cross section extending therethrough and defined by said side and said end walls. 100
4. A form for a baffle for a steam boiler having boiler tubes, comprising a row of members across the boiler tubes arranged end to end and supported on the tubes, said members having their ends locked together to hold them in alignment and each of said members having an opening extending therethrough from top to bottom. 105
5. A form for a baffle for a steam boiler having boiler tubes, comprising a row of members across the boiler tubes arranged end to end and supported on the tubes, the adjacent ends of said members being provided with interengaging ribs and recesses 115 and each of said members having an opening extending therethrough from top to bottom.
6. In a steam boiler, boiler tubes, and a baffle extending across the tubes and comprising rows of members arranged end to end across the tubes and supported thereon, each member having an opening extending into the body portion of the member from at least one of its horizontal faces, and hardened plastic material between said members and in said recesses. 120
7. In a steam boiler, boiler tubes, and a baffle extending across the tubes and comprising rows of metallic members arranged 125
8. In a steam boiler, boiler tubes, and a baffle extending across the tubes and comprising rows of metallic members arranged 130

- end to end across the tubes and supported thereon and having a good thermal engagement with said tubes, each member having an opening extending into the body portion 5 of the member from at least one of its horizontal faces, and hardened plastic material between said members and in said recesses.
8. In a steam boiler, boiler tubes, and a baffle extending across the tubes and comprising rows of metallic members arranged end to end across the tubes and supported thereon, each member having a vertical opening extending therethrough, and hardened plastic material between said members 10 and in said openings.
9. In a steam boiler, boiler tubes, and a baffle extending across said tubes and comprising hollow metallic members having flat side walls spaced apart and transverse 15 walls having outer surfaces conforming to and adapted to engage boiler tubes, and hardened plastic material between said members and in the spaces between said side walls and extending flush with the outer 20 surfaces thereof.
10. In a steam boiler, boiler tubes arranged in rows and a baffle extending across the tubes and comprising rows of metallic members each extending across a row of 25 boiler tubes and supported thereon, each member having an opening extending into the body portion of the member from at least one of its horizontal faces, with the tops of said members spaced from the next adjacent row of boiler tubes, and hardened plastic material between the rows of members and in said recesses.
11. In a steam boiler, boiler tubes arranged in rows and a baffle extending across 30 the tubes and comprising rows of metallic members each extending across a row of boiler tubes and supported thereon, each member having an opening therethrough between its horizontal faces, with the tops of 35 said members spaced from the next adjacent row of boiler tubes, and hardened plastic material between the rows of members and in said openings.
12. In a steam boiler, boiler tubes arranged in rows and a baffle extending across 40 the tubes and comprising rows of metallic members each extending across a row of boiler tubes and supported thereon, each member having side walls spaced apart and 45 transverse walls having outer surfaces conforming to and adapted to engage boiler tubes, and hardened plastic material between said members and in the spaces be-

tween said side walls and extending flush with the outer surfaces thereof. 60

13. In a steam boiler, boiler tubes arranged in rows with the tubes in the several rows staggered to form diagonal lanes, and a baffle extending across the tubes and comprising rows of metallic members each 65 extending across a row of boiler tubes and supported thereon, each member having side walls and curved end walls engaging boiler tubes and an opening extending therethrough and defined by said side and said 70 end walls, said members being constructed and positioned so that openings in adjacent rows of said members will permit the passage therethrough of a straight tube along each diagonal lane, and hardened plastic 75 material between said members and in said openings.

14. In a steam boiler, boiler tubes arranged in rows with the tubes in the several rows staggered to form diagonal lanes, and 80 a baffle extending across the tubes and comprising rows of metallic members each extending across a row of boiler tubes and supported thereon, each member having side walls and curved end walls engaging boiler 85 tubes and an opening extending therethrough and defined by said side and said end walls, the tops of said members being spaced from the next adjacent row of boiler tubes and the members in the next adjacent 90 rows, said members being constructed and positioned so that openings in adjacent rows of said members will permit the passage therethrough of a straight tube along each diagonal lane, and hardened plastic 95 material between the adjacent rows of said members and in said openings.

15. In a steam boiler, boiler tubes arranged in rows with the tubes in the several rows staggered to form diagonal lanes, and 100 a baffle extending across the tubes and comprising rows of metallic members each extending across a row of boiler tubes and supported thereon with the adjacent ends of said members locked together, each member having side walls and curved end walls 105 engaging boiler tubes and an opening extending therethrough and defined by said side and said end walls, said members being constructed and positioned so that openings in adjacent rows of said members will permit the passage therethrough of a straight tube along each diagonal lane, and hardened plastic material between said members and in said openings. 110

DAVID S. JACOBUS.
